UNITED STATES PATENT OFFICE.

JAMES M. BARIENGER, OF CARTHAGE, NEW YORK, ASSIGNOR OF ONE-HALF TO SANTA CLARA LUMBER COMPANY, OF CARTHAGE, NEW YORK.

DEVICE FOR REGISTERING PULP-BLOCKS, &c.

1,054,814.

Specification of Letters Patent.

Patented Mar. 4, 1913.

Application filed August 23, 1912. Serial No. 716,711.

To all whom it may concern:

Be it known that I, JAMES M. BARIENGER, a citizen of the United States, residing at Carthage, in the county of Jefferson and State of New York, have invented certain new and useful Improvements in Devices for Registering Pulp-Blocks, &c.; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in counting devices for attachment to pulp block conveyers, the object in view being to provide an automatically operated apparatus for registering not only the number of blocks which are conveyed, but also register blocks of different diameters.

The invention relates to various details of construction and combination of parts as will be hereinafter more fully described and then specifically defined in the appended claim.

The invention is clearly illustrated in the accompanying drawings, which, with the letters of reference marked thereon, form a part of this application, and in which,

Figure 1 is a perspective view of a portion of a conveyer showing the application of my registering device as applied thereto.

Fig. 2 is a top plan view of the device. Fig. 3 is an enlarged detail view of the counters and the means for actuating same, and Fig. 4 is a bottom plan view of the apparatus.

Reference now being had to the details of the drawings by letter A designates the frame of a conveyer, preferably slightly trough shaped, and in which the usual endless conveyer chain B travels. Fixed to said frame are the bearing members C holding the pivotal pins D which receive the bearing members E secured each to a plate or wing F. Secured to each plate or wing, there being two of the latter as shown, and which are disposed at angles to each other and over said conveyer frame, is a bar H projecting below the lower edge of the plate. Pivoted to the lower end of each of

said bars is a rod G, and the inner end of each of said rods is in turn pivoted to a link J, mounted upon a pivotal pin I secured to the frame. A coiled spring is fastened one to each end of said link, and their outer ends to the frame and which springs tend to normally hold the plates so that their free ends will be in the path of the block carried forward by the conveyer chain, and to return the plates to their normal positions, after the plates have been swung outward by a passing block.

Positioned on a projection Q of the frame, are the series of registering devices, arranged in two rows, and each register is provided with a trip O, and each is adapted to count the blocks of a distinct diameter, while a single register makes a registration of the total number of blocks which pass the plates or wings. Fastened to one of the plates, is a bracket member P, which as the plate to which it is attached, swings out, incident to the passing of a block, contacts with one or another of said trips, according to the diameter of the block passing. For instance, if the block passing is of the minimum diameter of blocks which are utilized, the bracket arm will contact with the first trip of the first register. Should the block be of a slightly larger diameter than the first block, the next trip would be actuated to register the block. The registers at the extreme outer ends of the series would, it will be noted register the blocks of the greatest diameters.

To determine how many blocks of a particular diameter have been conveyed, the total number registered by a particular register may be subtracted from the total indicated by the adjacent register which makes a registration of the blocks of the next greater diameter. The total shown on the register which registers the blocks of the smallest diameter, will also show the entire number of blocks of all diameters which have been conveyed.

What I claim to be new is,—

A device for registering pulp blocks, &c., comprising a conveyer frame, a conveyer chain therein, plates pivotally mounted upon the frame, and disposed in the path of blocks carried by the chain, registers each provided with a trip, a bracket member se-

cured to each plate and adapted, as the latter is moved by a block, to contact with a trip of a register, a bar secured to each plate, and pivotal spring connections between said bars, tending to return the plates to their normal positions after being actuated by a block, as set forth.

In testimony whereof I hereunto affix my signature in the presence of two witnesses.

JAMES M. BARIENGER.
